ONE-PIECE MOLDED COMBINED CHAIR SEAT
AND BACK

William James Bargen, Waukegan, Ill.

Application February 26, 1957, Serial No. 44,993

Term of patent 14 years

(Cl. D15—1)

Fig. 1

Fig. 2

The dotted line showing in the drawing is for illustrative purposes only.

I claim:

The ornamental design for a one-piece molded combined chair seat and back, as shown and described.
